(57) **CLAIM**

The ornamental design for an electronic device with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design; and, FIG. 2 is another embodiment thereof.

The dashed broken lines in the figures show portions of electronic device with graphical user interface that form no part of the claimed design.

The dot-dash broken lines in the figures show boundaries that form no part of the claimed design.

FIG. 2 is illustrated to show contrasting appearance. Areas of the electronic device with graphical user interface that appear in gray and black represent areas with contrasting appearances.
